UNITED STATES PATENT OFFICE.

GEORGE W. BEAVER, OF MANN'S CHOICE, PENNSYLVANIA, ASSIGNOR OF THREE-FOURTHS TO HARVEY GREGORY, FRANK LEONARD, AND J. A. WYNNE, OF SAME PLACE.

THILL-COUPING.

SPECIFICATION forming part of Letters Patent No. 325,648, dated September 8, 1885.

Application filed May 23, 1885. (No model.)

To all whom it may concern:

Be it known that I, GEORGE W. BEAVER, a citizen of the United States, residing at Mann's Choice, in the county of Bedford and State of Pennsylvania, have invented certain new and useful Improvements in Thill-Couplings, of which the following is a specification, reference being had therein to the accompanying drawings.

10 My invention relates to thill-couplings; and it consists in the construction and arrangement of the parts, which will be more fully hereinafter described, and pointed out in the claims.

15 The object of my invention is to provide a thill-coupling adapted for use in connection with any style of vehicle, and one which shall be simple and effective in its construction, easily and readily understood, and cheaply 20 manufactured. I attain these objects by the construction of the device illustrated in the accompanying drawings, wherein like letters of reference indicate similar parts in the several views, and in which—

25 Figure 1 is a perspective view of my improved thill-coupling. Fig. 2 is a front elevation of the same. Fig. 3 is a transverse vertical section on line X X, Fig. 2, showing an anti-rattler attached thereto. Fig. 4 is a 30 sectional elevation of the anti-rattler, adjusting-screw, and supports. Fig. 5 is a modified form of the locking-spring.

A represents the axle-beam, to which is secured in the usual manner the clip B. As 35 in the ordinary form of thill-couplings, two extensions, C C', are cast integral with the clip B. These extensions have holes bored through their sides, through which a sliding bolt, D, passes. The flange or projection c' is formed 40 at the lower portion of the extension C', and the half-head d on the bolt D, when turned a sufficient distance, engages with the said flange c', and acts to secure the bolt D and prevent it from becoming accidentally detached. The 45 extension C' has a flanged projection, c', cast integral therewith, with which the flanged half-head d of the locking-bolt D engages. On the other end of the locking-bolt an operating-lever, D', is secured, by means of which the bolt

D may be withdrawn from the hole in the extensions C C'.

To the under side of extension C a headed pin, c', is secured. Around this pin c' a flat locking-spring, C', is looped, one portion of said spring extending in toward the axle-beam 55 A and resting thereon, and the other portion extending outward toward and engaging with the operating-lever D' by a loop, c', and from this point it extends outward a short distance, so as to form a projection, c', by which it may 60 be operated.

As illustrated in Fig. 5, a wire spring may be used and substituted in the place of the flat spring just described, operating in the same manner. This spring C' acts to secure 65 the lever D' and prevent the accidental displacement of the sliding bolt D.

As illustrated in Figs. 3 and 4, an anti-rattler, F, is secured to the extended portion of the clip-securing plate E, having a shoulder, 70 e, which prevents the box f' of the rattler from turning. A suitable adjusting thumb-screw, f, is seated in the plate E, extending vertically upward, and has a shoulder, f', formed on the end thereof. A metal box, f', 75 rests upon shoulder f', being fastened thereon by a reduced projecting portion, f', of screw f, which is headed on the inside bottom of box f', and prevents the said screw from becoming disengaged therefrom and dropping 80 out. In the box f' a rubber cushion, f', is placed and secured by suitable means, and on the top of this rubber cushion a metal cap or covering, f', is secured, which prevents the direct wear of the thill-iron upon the said 85 rubber cushion. By the thumb-screw f the anti-rattler is adapted to fit any style of thill-iron and be made to conform to thill-irons of varying dimensions.

The operation of my improved thill-coupling is as follows: The operating-lever D' is released from engagement with the spring C', and the sliding bolt D is turned until the flange on the half-head d clears the flanged projection c' of the extension C'. The sliding bolt D is then drawn out and the thill placed in the space between the two extensions C and C', and the bolt shoved back to its place.

Normally the lever D' engages with the spring C², by which it is locked in place.

Various mechanical changes could be made and substituted for those shown and described 5 without in the least departing from the nature and principle of my invention.

Having thus described my invention, what I claim as new, and desire to secure by Letters Patent, is—

- 10 1. In a thill-coupling, the combination of a clip having extensions C C', a sliding bolt having free movement in said extensions and provided with an operating-lever, and a spring locking device secured to the under side of
- 15 the extension C at or about its middle portion, and having one of its ends resting on the axle-beam and the other looped and securing the sliding-bolt lever, substantially as described.

2. In a thill-coupling, the combination of the clip B, having extensions C C', a sliding bolt, D, having a lever, D', moving in said extensions, a spring, C², on the under side of extension C, one end of which spring rests against the axle-beam A, and the other looped, as c³, and engaging the lever D', and an anti-rattler, F, constructed substantially of the form described, for the purposes specified.

In testimony whereof I affix my signature in presence of two witnesses.

GEORGE W. BEAVER.
